Pine Bluff, Ark.

Application January 12, 1939, Serial No. 250,603

18 Claims. (Cl. 200—114)

This invention relates generally to fusible switching devices, such as fusible circuit interrupters or fuse switches, used for the purpose of disconnecting an electrical circuit upon the attainment of a predetermined current therein.

Among the objects of the present invention may be noted: (a) the provision of means for disconnecting certain normally alive elements of the device in response to the blowing or rupture of the fuse link; (b) the provision of an actuating and an actuated element rotatively movable on a common axis for accomplishing the disconnection; after a predetermined movement of the actuating element, the actuating element moving to a readily visible position for indicating the condition of the fuse switch; (c) the provision of a support for the connecting member of the switch which cooperates with a resilient contact member to maintain the connecting member in the closed position; (d) the provision of means for disconnecting certain normally alive elements of the fuse switch while the connecting member is manually held in the closed position; (e) the provision of a switch embodying a contact member, and means for limiting the movement of the contact member; (f) the provision of an actuating element normally restrained by a tensioned fuse link and a contact arranged to be actuated in response to movement of the actuating element, the elements being so related and arranged that the actuated contact is held in a circuit closing position independent of the tension of the fuse link; (g) the provision of means for delaying the movement of the contact until the separated portions of the fuse link following its fusing are mechanically separated for a substantial distance; and (h) guide means for directing the path of movement of the connecting member to the closed position.

As may be noted from the objects above stated, our fuse switch embodies several improvements not found in devices of this character which are now available. Present switches which embody means for disconnecting the fuse tube in response to the rupture of the fuse link are generally of a "drop-out" type; that is, one in which the fuse tube is unlatched when in the closed position, and caused or permitted to fall to an open position when the fuse link fuses. In such constructions, the tension to which the fuse link is subjected is a function of the contact pressure when the fuse tube is in the closed position. This organization has the inherent difficulty of a fuse link tension which varies directly with the contact pressure. The desired arrangement is one in

which there is a high contact pressure and a low fuse link tension. Our invention is an arrangement in which the fuse link tension is entirely independent of the contact pressure. In addition, the "dropping-out" of the fuse switch is undesirable, as it results in an inverted tube when the latter is in the open position, which may fill with rain water and be damaged thereby. In the present invention, the fuse tube remains unmoved, and in the closed position, but at the same time is effectively open-circuited in response to the blowing of the fuse link. A further advantage in the present invention, not found in prior structures, is in the arrangement in which the "open-circuiting" of the device is independent of the manual operation of the switch; that is, the fuse tube cannot be manually held so that it will remain in the circuit if the fuse link is ruptured by blowing. In other words, our fuse switch is "trip-free" of the manipulating eye.

Other advantages and objects will be apparent from the following description and claims, taken in connection with the accompanying drawings forming a part of this application, in which:

Fig. 1 is a side elevational view of the switch shown in the closed circuit position.

Fig. 2 is a fragmentary section taken along the line II—II of Fig. 1.

Fig. 3 is a fragmentary side elevation showing the position of the lower elements of the switch immediately following the fusing of the fuse link.

Fig. 4 is another fragmentary side elevational view, illustrated partly in section, and showing the final position taken by the lower elements of the switch following the rupture of the fuse link.

Fig. 5 illustrates, partly in section, the connecting member of the switch, in the open or inverted position, as after manual manipulation preparatory to re-fusing the switch.

Fig. 6 is a fragmentary front view, with the fuse tube broken away to better illustrate the elements. Similar reference characters indicate corresponding parts throughout the several views of the drawings.

Referring more in detail to the drawings, it may be seen that our fuse switch may be conveniently divided, for purposes of description, into two parts; the first being the substantially stationary or fixed members, including the fixed terminals, and the second being the connecting member which is movable and removable with respect to the fixed members.

The first part includes the longitudinally extending insulator 10, of porcelain or other suitable insulating material, which is arranged to

be supported by the bracket 11, the latter being rigidly secured to the insulator 10 between the ends thereof. Only the portion of the bracket 11 pertaining to the present invention is shown, as it may be of any suitable design well known in this art. A line terminal 13, in the form of a contact-receiving clip, is rigidly secured to the upper end of the insulator 10 by the outwardly extending upper terminal support 12, in any suitable manner, and a line connecting terminal 14 provides means for electrically connecting the line conductor 15 to the upper terminal 13.

A fuse assembly or connecting member support 16 encircles the lower end of the insulator 10, and is rigidly secured thereto by the bolt and nut 18. The end portions of the member 16 extend outwardly in the same direction as that of the upper terminal support 12, being held in substantially parallel relationship one to the other by the spacer 17, and at the outer ends are provided with a pair of hooks 43 and 44. An outwardly extending load terminal 19, of resilient conducting material, encircles the insulator 10 at a position in spaced relationship with the bracket 11 and the supporting member 16, and is rigidly secured to the insulator 10 between the latter members. The load or lower terminal 19 is preferably in the form of two parallel substantially horizontal outstanding arms, as shown in Fig. 6, being held in parallel relation by means of the load terminal clip 20. A load connecting terminal 21 provides means for electrically connecting the load conductor 22 to the load terminal 19. From the above description, it may be seen that the upper terminal support 12, the bracket 11, the load terminal 19, and the supporting member 16 are all mounted on the insulator 10 in insulated spaced relationship to each other.

The movable and removable connecting member or fuse assembly of the switch includes a hollow tube of insulating material 23, to the lower end of which is rigidly secured, by means of the set screw 25, a fuse tube support 24. The latter encompasses the lower end of the tube 23, and is provided with a pair of oppositely extending pintles 26 and 27, arranged to seat or rest in the hooks 43 and 44 respectively, and thereby pivotally support the connecting member at its lower end. A pair of outwardly extending portions 30 extend upwardly from the pintles 26 and 27, as shown in Fig. 4, and are arranged to frictionally engage the inner surface of the hooks 43 and 44, and thereby guide the rotative movement of the connecting member.

At its upper end, the fuse tube 23 has threadedly secured thereto the upper or line terminal-engaging contact 40, which is disposed and formed to enter the line terminal 13, and thereby support the upper end of the connecting member. For convenience in manipulating the connecting member from the open to the closed position, the eyes 41 and 28 are integrally formed on the members 40 and 24 respectively.

An integral upwardly extending portion 29 of the fuse support 24 is positioned between the fuse tube 23 and the insulator 10, and below the terminal 19, and provided with a horizontally extending opening through which the pivot 39 passes, as shown in Figs. 2 and 6. A bifurcated fuse link terminal member 32 is mounted on the pivot 39 for rotation thereabout, and extends first across the tube 23, and thence downwardly therealong to the lower end thereof, being provided at the lower end with the fuse link con-

necting terminal 33. A fuse link 31, fastened at its upper end to the upper contact 40 of the tube 23 by the screw plug 42, normally extends downwardly through the tube 23, and has its lower end fastened to the fuse link terminal member 32 by means of the fuse link connecting member 33, so that, under the normal condition with the fuse link unfused, the downwardly extending portion of the fuse link terminal member 32 lies along and close to the lower end of the fuse tube 23. A tension spring 38, having one end attached to an upwardly extending portion 36 of the fuse link terminal member 32, and the other end to the eye portion 28 of the fuse tube support 24 continually urges the fuse link terminal member 32 in a direction to tension the fuse link 31, and also to rotate the lower portion of the fuse link terminal member 32 away from the fuse tube 23.

A bifurcated load or lower terminal-engaging contact 34 is also mounted on the pivot 39 for pivotal movement in the same direction as that of the fuse link terminal member 32, the contact 34 extending upwardly from its pivotal mounting to engagement with the terminal 19, and being so positioned and formed that the direction of downward pressure of the resilient terminal 19 is along a line through the center of the pivot 39. This arrangement eliminates any tendency to move the contact 34 out of its normal terminal-engaging position, and it is normally retained in this position by the frictional engagement of the respective members.

The terminal 19 cooperates with the contact 34 and the pivot 39 so that the direction of pressure on the connecting member is between the pintles 26 and 27 and the insulator 10, or so as to tend to rotate the entire fuse tube assembly in a counterclockwise direction about the pintles. This arrangement maintains the connecting member in the closed position when the fuse link is unfused, and makes unnecessary any latching device for holding the upper end of the fuse tube in the proper position.

With the connecting member in the normal closed position, and with the fuse link unfused, it may be seen that a series circuit is provided through the switch from the line terminal 13 to the fuse link 31, thence through the latter to the fuse link terminal member 32, thence through the latter to the lower terminal contact member 34, and thence through the latter to the lower terminal 19. Under the above stated conditions, the elements of the switch occupy the positions illustrated in Fig. 1. It will now be apparent that the fuse link 31 is tensioned by the spring 38, but that the portion of the lower surface 45 of the contact 34 which lies in the path of movement of the portion 46 of the fuse link terminal member 32 is spaced from the latter, so that no force tending to move the contact 34 is impressed thereon by the spring 38; that is, the movable contact member is held in the closed position independent of the tensioned fuse link.

Once in the normally closed circuit position, as above stated, the contact member 34 is maintained in the closed position independent of the tension of the fuse link 31; however, it is necessary to provide means for positioning the contact member to accomplish this result when the connecting member is moved from the open position shown in Fig. 5, to the closed position shown in Fig. 1. For this purpose, an integral bar 35, joining the legs of the bifurcated contact member 34 at their respective lower ends, is arranged to limit the movement of the contact 34 in a

clockwise direction by engaging a portion of the tube support 24, and the counterclockwise movement is limited by the engagement of the sloping portions 37 of the contact member 34 with the top surfaces of the laterally extending arms of the fuse link terminal member 32.

Assume now that the switch is in the closed circuit position illustrated by Fig. 1, and that the fusible element 47 of the fuse link 34 is fused by an abnormal current in the circuit. Upon the parting of the fuse link 34, the fuse link terminal member 32 is no longer held by the fuse link 34, and is rotated about the axis of the pivot 33, under the influence of the spring 38, until the impacting portion 48 reaches, in its path of movement, the portion 46 of contact 34. Fig. 3 illustrates the position of the elements at this stage; that is, just prior to striking the contact member 34. It should be noted that, as the fuse link terminal member rotates, the lower end of the fuse link 34 is extracted from the tube 23. This assures that the circuit-interrupting arc will be extinguished before the contact 34 is struck. It may also be noted that the fuse link terminal member travels over an appreciable arc before impact occurs, thereby acquiring substantial momentum before the instant of impact.

Following impact, the elements assume the positions indicated in Fig. 4. The terminal contact member 34, having been struck by the fuse link terminal member 32, has been driven to the disengaged position with respect to the load terminal 19. The portion of the insulator 10 between the terminal 19 and the support 18 is now electrically interposed in series circuit relation with the fuse tube 23, the fuse link 34, the support 16 and the upper terminal 13, providing a definite open circuit or disconnection of these members from the load terminal 19. The fuse link terminal member 32 has moved under the bias of the spring 38 so that its lower portions now extend outwardly away from the tube, thus providing an easily visible indication that the fuse link has fused, and that the contact 34 has been actuated from the closed circuit to the open circuit position.

To re-fuse the switch, the eye 41 is moved outwardly and downwardly to rotate the connecting member, on the pintles 28 and 27, to the inverted position shown in Fig. 5. The assembly may then be lifted out of the hooks 43 and 44. It will be seen that both terminals of the switch are disconnected from the connecting member when it is in the position shown by Fig. 5, which is desirable from the standpoint of safety to the operator. Following removal of the connecting member, it may be refused, replaced in the hooks 43 and 44 in the inverted position, and rotated about the pintles 28 and 27 to again engage the respective terminals of the switch, as in Fig. 1. An additional safety feature may be noticed in the fact that the switch is "trip-free" of the manipulating eye 41; that is, the contact member 34 moves from the closed to the open position independent of the manipulation of the tube 23, and therefore the latter cannot be held in a position in series with the circuit if the fuse link has blown.

While we have shown and described herein a specific embodiment of our invention, it will be understood that this has been done to better illustrate its construction and operation, and that our invention is to be limited only as may be necessitated by the prior art and the appended claims.

We claim as our invention:

1. A fuse switch comprising an insulator, spaced switch terminals supported thereon, a fuse tube mounted on said insulator; a fuse link terminal member pivotally mounted on said tube at one side thereof, said fuse link terminal member spanning said tube and extending downwardly along the latter to a point adjacent the lower end of said tube, a fuse link extending through said tube and secured to said fuse link terminal member at its lower end and on the side of the tube opposite the pivotal mounting of said fuse link terminal member, a load terminal contact member pivoted on said tube and engaged with one switch terminal means including the serial arrangement of said fuse link, said fuse link terminal member and said load terminal contact member for electrically connecting said switch terminals and means responsive to rupture of said fuse link for disengaging said load terminal contact member from said one switch terminal.

2. In a fuse switch, spaced terminals, means supporting a fuse tube in series circuit relation with said terminals, a fuse link terminal member and a terminal-engaging contact member pivotally mounted on said fuse tube for rotation about a common axis, a fuse link within said tube having one end fastened thereto and the other end fastened to said fuse link terminal member, and resilient means urging said fuse link terminal member in a direction to tension said fuse link, said terminal-engaging contact member having a portion thereof positioned in the path of movement of said fuse link terminal member, the arrangement being such that said terminal-engaging contact member is struck a blow following a predetermined movement of said fuse link terminal member which occurs without movement of said contact member and thereby disengaged from the terminal upon rupture of said fuse link.

3. In a fuse switch, spaced terminals, a fuse tube, a swingably movable fuse link terminal member at the lower end of said tube, a swingably movable load contact member positioned in the path of movement of said fuse link terminal member and arranged to be engaged by the latter after its movement for a predetermined distance along said path while said contact member remains unmoved, resilient means urging said fuse link terminal member in a direction to engage said load contact member, and means including a fuse link extending through said tube electrically connecting said terminals, said fuse link being fastened to said fuse link terminal member and restraining the movement thereof.

4. In a fuse switch, spaced terminals, a fuse tube, a swingably movable fuse link terminal member and a swingably movable terminal contact member pivotally mounted at the lower end of said tube for rotation about a common axis, said terminal contact member having a portion thereof interposed in the path of movement of said fuse link terminal member, resilient means urging said fuse link terminal member in a direction to strike and initiate movement of said terminal contact member only after said fuse link terminal member has moved for a predetermined distance, and means including a fuse link extending through said tube electrically connecting said terminals, said fuse link being fastened to said fuse link terminal member and normally restraining the movement thereof.

5. A fuse switch comprising an insulator,

spaced terminals supported thereon, a fixed fuse tube mounted on said insulator, a swingably movable fuse link terminal member and a swingably movable terminal-engaging contact member pivotally mounted on said fuse tube at the lower end thereof for rotation about a common axis, said terminal-engaging contact member normally engaging one terminal of the terminals and having a portion thereof interposed in the path of movement of said fuse link terminal member, resilient means urging said fuse link terminal member so as to strike and initiate movement of said contact member in a direction to disengage the latter from said one terminal only after said fuse link terminal member has moved for a predetermined distance, and means including a fuse link extending through said fuse tube electrically connecting said terminals, said fuse link being fastened to said fuse link terminal member and normally restraining the movement thereof.

6. In a fuse switch, insulating means supporting relatively spaced terminals including an outwardly extending lower terminal of resilient conducting material, a connecting member movable between open and closed positions, said connecting member including a fuse tube, a swingably movable fuse link terminal member at the lower end of said tube, a swingably movable load contact member extending upwardly from the lower end of said tube in engagement with said outwardly extending lower terminal when said connecting member is in the closed position, said swingably movable load contact member having a portion thereof positioned in the path of movement of said fuse link terminal member for engagement by the latter after it has moved a predetermined distance along said path, means biasing said fuse link terminal so as to engage and initiate movement of said contact member away from said outwardly extending lower terminal only after said fuse link terminal member has moved over said predetermined distance, and means including a fuse link extending through said tube and electrically connecting said terminals, said fuse link being fastened to said fuse link terminal member and restraining the movement thereof when said fuse link is unfused.

7. A fuse switch comprising insulating means supporting relatively spaced terminals including an outwardly extending lower terminal of resilient conducting material, a fuse tube movable between open and closed positions, a fuse link within said tube electrically connecting said terminals, a swingably movable fuse link terminal member at the lower end of said tube, a swingably movable load contact member extending upwardly from the lower end of said tube in engagement with said outwardly extending lower terminal when said fuse is in the closed position and said fuse link is unfused, said swingably movable load contact member having a portion thereof positioned in the path of movement of said fuse link terminal member for engagement by the latter after it has moved a predetermined distance along said path, and means biasing said fuse link terminal so that it engages and initiates movement of said contact member away from said outwardly extending lower terminal only after moving said predetermined distance, said fuse link being fastened to said fuse link terminal member and restraining the movement thereof when said fuse link is unfused.

8. A fuse switch comprising insulating means supporting spaced terminals including an outwardly extending lower terminal of resilient con-

ducting material, a fuse tube movable between open and closed positions, a fuse link within said tube electrically connecting said terminals, a swingably movable fuse link terminal member and a swingably movable lower contact member pivotally mounted at the lower end of said tube for rotation about a common axis, said lower contact member extending upwardly from the lower end of said tube and engaging said lower terminal when said fuse tube is in the closed position and said fuse link is unfused, said swingably movable lower contact member having a relatively stationary portion positioned in the path of movement of said fuse link terminal member for engagement by the latter only after it has moved a predetermined distance along said path whereby terminal-disengaging movement of said lower contact member is initiated, and means biasing said fuse link terminal in a direction to engage and move said contact member away from said outwardly extending lower terminal, said fuse link being fastened to said fuse link terminal member and restraining the movement thereof when said fuse link is unfused.

9. In a circuit interrupter, a terminal member, a contact member movable to and away from said terminal member to respectively close and open the circuit, a relatively movable fuse link terminal member arranged to move a predetermined distance while said contact member remains unmoved and to strike, and thereby initiate movement of said contact member to open the circuit, and a fuse link fastened to said fuse link terminal member and restraining the movement thereof.

10. In a circuit interrupter, a terminal member, a contact member movable to and away from said terminal member to respectively close and open the circuit, a spring-pressed movable fuse link terminal member arranged to strike said contact member following an unimpeded movement of said fuse link terminal member which occurs while said contact member remains unmoved and over a predetermined path sufficiently long to impart thereto substantial momentum, and a fuse link serially connected in said circuit and fastened to said fuse link terminal for restraining the movement thereof.

11. A fuse switch comprising insulating means supporting spaced terminals including an outwardly extending lower terminal of resilient material, a fuse tube movable between open and closed positions, a fuse link within said tube electrically connecting said terminals, a swingably movable fuse link terminal member and a swingably movable lower contact member pivotally mounted at the lower end of said tube for rotation about a common axis, said lower contact member extending upwardly from its pivotal mounting and engaging said lower terminal when said fuse tube is in the closed position and said fuse link is unfused, said swingably movable lower contact member having a relatively stationary portion thereof positioned in the path of movement of said fuse link terminal member for engagement by the latter after it has moved a predetermined distance along said path, said relatively stationary portion remaining unmoved while said fuse link terminal member moves over said predetermined distance and moving only after being struck by said fuse link terminal member, and means responsive to the rupture of said fuse link for actuating said fuse link terminal member.

12. A fuse switch comprising insulating means

supporting spaced terminals including an outwardly extending lower terminal of resilient material, a fuse tube movable between open and closed positions, a fuse link within said tube electrically connecting said terminals, a swingably movable fuse link terminal member and a swingably movable lower contact member pivotally mounted at the lower end of said tube for rotation about a common axis, said lower contact member extending upwardly from its pivotal mounting and engaging said lower terminal when said fuse tube is in the closed position and said fuse link is unfused, said swingably movable lower contact member having a relatively stationary portion thereof positioned in the path of movement of said fuse link terminal member for engagement by the latter only after it has moved a predetermined distance along said path, said relatively stationary portion remaining unmoved while said fuse link terminal member moves over said predetermined distance and moving only after being struck by said fuse link terminal member, said fuse link having the upper end thereof fastened to said tube and the lower end fastened to said fuse link terminal member, and means biasing said fuse link terminal member in a direction to engage and move said contact member away from said outwardly extending lower terminal.

13. In a fuse switch, a fuse tube, a supporting member rigidly secured to said tube, a terminal, and a contact member arranged for movement between an engaged and a disengaged position with respect to said terminal, a fuse link terminal member pivotally mounted on said supporting member and so constructed and arranged as to strike and thereby actuate said contact member from the engaged to the disengaged position following a predetermined movement of said fuse link terminal, said contact member remaining unmoved while said predetermined movement occurs and moving only after being struck by said fuse link terminal member, and biasing means urging and a fuse link restraining said fuse link terminal member.

14. In a fuse switch, spaced terminals, means supporting a fuse tube in series circuit relation with said terminals, a fuse link terminal member and a terminal-engaging contact member pivotally mounted on said fuse tube for rotation about a common axis, a fuse link within said tube having its ends fastened respectively to said fuse tube and to said fuse link terminal member, said fuse link terminal member extending across said fuse tube and downwardly along said fuse tube when said fuse link is unfused, and means responsive to the rupture of said fuse link for actuating said terminal-engaging contact member to the disengaged position following a predetermined movement of said fuse link terminal member, the said predetermined movement rotating said fuse link terminal member so that the downwardly extending portion of the latter swings outwardly away from the fuse tube to an indicating position.

15. In a fuse switch, spaced terminals, means supporting a fuse tube in series circuit relation with said terminals, said fuse tube having

mounted thereon for limited rotation about a common axis and in the same direction a fuse link terminal member and a terminal-engaging contact member, said fuse link terminal member extending laterally across said fuse tube and normally downwardly therealong, a fuse link within said tube normally electrically connecting said terminals, said fuse link having its ends fastened respectively to said tube and to said fuse link terminal member, resilient means biasing said fuse link terminal member for rotation in a direction to tension said fuse link, and means responsive to a predetermined movement of said fuse link terminal member under the influence of said resilient means and following the rupture of said fuse link for actuating said contact-engaging member to the disengaged position, the said predetermined movement rotating said fuse link terminal member so that the normally downwardly extending portion thereof moves outwardly away from the fuse tube to an indicating position.

16. A fuse switch comprising an insulator, spaced upper and lower terminals mounted thereon, and a connecting member movable from open to closed position pivotally mounted at its lower end, said connecting member including a lower terminal contact member arranged to engage the lower terminal when the connecting member is in the closed position, said lower terminal being resilient and arranged to react on said connecting member in a direction to maintain the latter in the closed position.

17. A fuse switch comprising an insulator, spaced upper and lower terminals mounted thereon, a connecting member supported on said insulator and movable from the open to the closed position, means for pivotally mounting said connecting member at an elevation below said lower terminal and in lateral spaced relationship with said insulator, said connecting member having a portion thereof extending upwardly to said load terminal, and said load terminal being resilient and arranged to press said portion downwardly between the pivotal mounting of said connecting member and said insulator, whereby said connecting member is maintained in the closed position.

18. A fuse switch comprising an insulator, spaced terminals thereon including an upper terminal at the upper end thereof and a resilient outwardly extending lower terminal, a connecting member movable from the open to the closed position supported on said insulator, and means for pivotally mounting said connecting member at an elevation below said lower terminal and in lateral spaced relationship with said insulator, said connecting member having a portion thereof extending upwardly in resilient engagement with said outwardly extending lower terminal in a vertical plane which is positioned between the insulator and the pivotal mounting of the connecting member, whereby the reaction of said resilient outwardly extending lower terminal on said connecting member is in a direction to rotate the latter toward the closed position.
